APPARATUS FOR PURIFYING PLATING SOLUTIONS

Robert H. Tull, East Springfield, Mass., assignor to Westinghouse Electric & Manufacturing Company, East Pittsburgh, Pa., a corporation of Pennsylvania

Application October 9, 1936, Serial No. 104,910

8 Claims. (Cl. 204—5)

This invention relates to apparatus for purifying plating solutions.

In plating surfaces with a covering of metal, the plating solution employed becomes saturated with impurities formed by the chemical reaction of the plating solution. These impurities so interfere with the plating process that they must be removed or the solution must be discarded. In the apparatus employed heretofore for claiming the plating solutions, it was necessary to stop the purifying operation and clean the apparatus to remove the impurities therefrom. Where such an apparatus is employed, the expense incurred by interrupting the purifying process to clean the apparatus renders the apparatus undesirable.

An object of this invention is the provision of apparatus for effecting the continuous removal of impurities from plating solutions.

Another object of this invention is the provision of apparatus for removing impurities from plating solutions whereby the apparatus may be cleaned without interrupting the removal of impurities from the solution.

Other objects will become apparent from the following description when taken in conjunction with the accompanying drawing, the single figure of which is a diagrammatic view of the apparatus embodying the teachings of this invention.

As illustrated in the accompanying drawing, the apparatus for removing the impurities from a plating solution comprises a circulating system 10 connected to a plating tank 12 which contains a suitable plating solution (not shown) for the circulation of the plating solution from and to the plating tank.

In order to remove the impurities from the plating solution as it flows through the circulating system 10, a plurality of settling tanks 14 and 16 are provided associated with the circulating system. The settling tanks 14 and 16 are connected by means of the inlet pipes 18 and 20, respectively, to a supply pipe 22 through which the plating solution flows from the plating tank 12 to the respective settling tanks.

In order to insure a positive flow of the plating solution from the plating tank 12 to the settling tanks, a liquid pump 24 is disposed associated with the circulating system to force the plating solution from the plating tank 12 to the settling tanks 14 and 16 under pressure. The liquid pump 24 may be of any of the well known types and is adapted to be actuated by means of a motor 26 which is connected to some suitable source of power (not shown).

In order to return the plating solution to the plating tank 12, suitable outlet pipes 28 and 30 are disposed in settling tanks 14 and 16, respectively, and are connected to a return pipe 32 through which the plating solution flows to the plating tank 12.

Valves 34 and 36 are disposed in the inlet pipe 18 and outlet pipe 28, respectively, of the settling tank 14 and valves 38 and 40 are disposed in the inlet pipe 20 and the outlet pipe 30, respectively, of the settling tank 16 for controlling the flow of the plating solution to and from the settling tanks or for isolating either of the settling tanks from the circulating system as will be explained more fully hereinafter.

In order to insure a positive flow of the plating solution from the settling tanks when either valve 36 or 40 is opened, a liquid pump 42 similar to liquid pump 24 is disposed in the return pipe 32 of the circulating system between the outlet pipes 28 and 30 and the plating tank 12 to force the plating solution under pressure to the plating tank. The liquid pump 42 is disposed to be actuated by means of a suitable motor 44 which is connected to a suitable source of power (not shown), and may be energized for operation, as desired.

Since the impurities formed in the plating solution during the plating operation are usually of the type whereby they will crystallize and settle out of the solution when the temperature of the solution is lowered to a predetermined value, refrigerating means 46 and 48 are associated with settling tanks 14 and 16, respectively, for effecting a reduction in temperature of the solution or liquid contained in the settling tanks. The refrigerating apparatus 46 and 48 may be of any suitable type and may be operated simultaneously or separately, as desired. It is to be preferred that the refrigerating apparatus be maintained out of contact with the solution in the settling tanks.

As illustrated in the drawing, the supply pipe 22 passes through the return pipe 32 to provide a heat exchanger. This is desired since the plating solution withdrawn from the plating tank 12 is usually warm, whereas the plating solution withdrawn from the settling tanks is too cool to supply directly to the plating tank 12. By providing the heat exchanger thus associated with the circulating system, the heat is removed from the plating solution as it flows to the settling tanks from the plating tank 12 and is transferred to the cooled and purified plating solution to warm it before it is admitted to the plating

tank. Efficient operation of the purifying apparatus is thus obtained, since the plating solution from the plating tank 12 that is cooled in the heat exchanger may be more easily refrigerated in the settling tanks.

5 In order to provide for the cleaning of the circulating system and particularly the settling tanks 14 and 16, provision is made for supplying flushing fluid to the circulating system. The flushing fluid, such as tap water, may be supplied 10 to the circulating system through inlet 50 and removed therefrom through the outlet 52. Valves 54 and 56 are provided in the inlet and outlets 50 and 52, respectively for controlling the admission 15 of the flushing fluid to the circulating system. Valves 58 and 60 are disposed in the supply pipe 22 and return pipe 32, respectively, in the circulating system adjacent to the plating tank 12 for disconnecting the circulating 20 system from the plating tank when it is desired to flush the apparatus to remove the impurities.

In operation, when it is desired to perform the plating of objects, valves 58 and 60 are actuated to their closed position to disconnect the 25 plating tank 12 from the circulating system 10. The plating solution is then supplied to the plating tank 12. After a time interval, it is found that the plating solution in the tank 12 contains 30 impurities which render the plating process inefficient. In employing the apparatus of this invention to remove the impurities from the plating solution the operation is as follows:

One of the settling tanks, say 16, is isolated 35 from the circulating system by actuating the valves 40 and 38 in the outlet 30 and inlet 20, respectively, to their closed position. Valve 36 in the outlet pipe 28 of settling tank 14 is also actuated to its closed position to prevent the flow of fluid from the settling tank 14 while valve 40 34 in the inlet pipe 18 is actuated to its open position to permit the flow of fluid to the settling tank. With the valves in the position as indicated, valve 54 in the inlet pipe 50 is actuated 45 to its open position to permit the flow of a flushing fluid, such as tap water, into the supply pipe 22 where it is forced by means of the liquid pump 24 to flow through the inlet pipe 18 to the settling tank 14. When a suitable amount of flushing fluid is in the supply pipe 22 and the 50 settling tank 14, valve 56 is actuated to its closed position to cut off the supply of the flushing fluid to the supply pipe 22. The pump 24 functions to force the flushing fluid under pressure from the supply pipe 22 into the settling tank 14. 55 After the flushing fluid is forced out of the supply pipe 22 into the settling tank 14, the valve 34 is actuated to its closed position and the flushing fluid is refrigerated in the settling tank to lower its temperature to approximately the 60 freezing point of the flushing fluid.

When the temperature of the flushing fluid is reduced to a predetermined value, valve 58 is actuated to its open position to permit the flow of plating solution from the plating tank into the supply pipe 22. Valve 38 in the inlet pipe 65 20 is also opened to permit the flow of the plating solution from the supply pipe 22 into settling tank 16. At the same time valve 36 in the outlet pipe 28 of settling tank 14 and valve 56 in the outlet pipe 52 are opened to permit the flow of the flushing fluid from the settling tank 14 out of the circulating system. Liquid pumps 24 and 70 42 may be actuated to simultaneously effect the flow of the liquids in pipes 22 and 32, respectively, under pressure.

As the plating solution flows from the plating tank 12 through the heat exchanger, the heat of the plating solution is so transferred from the solution in supply pipe 22 to the refrigerated flushing fluid in pipe 32 that the temperature of the plating solution is lowered to approximately 5 60° F. When the flushing fluid is forced out of the circulating system and a predetermined amount of the plating solution is forced into the settling tank 16, the liquid pumps 24 and 42 10 are deenergized and the valve 56 in the outlet pipe 52 of the circulating system and valve 36 in the outlet pipe 28 of the settling tank 14 are actuated to their closed position. The plating solution in the settling tank 16 is then refrigerated 15 to approximately 25° F. to cause a crystallization of the impurities in the solution. When the impurities crystallize they settle out of the solution and remain on the bottom and side walls of the settling tank.

20 After the plating solution in the settling tank 16 is refrigerated, valve 34 in the inlet 18 to settling tank 14 may be actuated to its open position to permit the flow of the impure plating solution from the supply pipe 22 to the settling tank 14 and valve 40 in the outlet pipe 30 of settling tank 16 may be actuated to its open position to permit the flow of the purified plating solution through the return pipe 32 to the plating tank 12, it being understood that valve 60 is actuated 30 to its open position after valve 56 is actuated to its closed position. The liquid pumps 24 and 42 may then be actuated to force the fluid under pressure through the supply pipe 22 and return pipe 32, respectively.

When a suitable amount of the plating solution is pumped into the supply pipe 22 to fill the settling tank 14, valve 58 may be actuated to its closed position to disconnect the supply pipe 22 from the plating tank 12. After the plating solution in the supply pipe 22 and return pipe 32 is forced into the settling tank 14 and plating tank 12, respectively, the operation of liquid pumps 24 and 42 may be stopped and valve 34 may be actuated to its closed position to isolate settling 45 tank 14 from the circulating system.

Since it sometimes takes several hours for the impurities to crystallize out of the plating solution in the settling tanks, the circulating system may be cleaned while one of the settling tanks 50 contains plating solution without interrupting the refrigeration and purification of the plating solution in the isolated settling tank. The cleaning of the circulating system may be accomplished by forcing the flushing fluid through the supply pipe 22, settling tank 16 and return pipe 32 to the outlet pipe 52.

After settling tank 16 is thus cleaned, valves 54 and 56 in the inlet and outlet pipes 50 and 52, respectively, from the circulating system may 60 be actuated to their closed position and valves 58 and 60 may be actuated to their open position to connect the circulating system with the plating tank 12. When the impurities are crystallized and settled out of the solution in the settling tank 14, valve 36 may be actuated to its open position to permit the flow of the purified plating solution to the plating tank 12 and the impure plating solution may then be supplied to the plating tank 16 after first actuating valve 7 40 in the outlet pipe 30 of the settling tank 16 to its closed position to prevent the flow of the plating solution from the settling tank. Settling tank 14 may then be cleaned after first settling the valves, as hereinbefore indicated, and then

forcing the flushing fluid under pressure through the settling tank.

This apparatus has proven to be of special benefit in purifying tin plating solutions, since it effectively removes or so lowers the sodium carbonate normally formed in the plating solution during the plating operation that the plating operation may be efficiently and economically performed. As is evidenced from the description of operation given hereinbefore, it is seen that this apparatus has a further advantage in that the purified plating solution is returned to the plating tank at nearly the operating temperature of the plating solution. Further, the use of the settling tanks, as hereinbefore described, permits the reclaiming of the plating solution during the plating operation to be continuous without loss of time in cleaning the settling tanks and without interrupting the purification of the plating solution.

Although this invention has been described with reference to a particular modification thereof, it is, of course, to be understood that it is not to be limited thereto except insofar as is necessitated by the prior art and the scope of the appended claims.

I claim as my invention:

1. Apparatus for the continuous removal of impurities from plating solutions comprising, in combination, a plating tank for containing the plating solution, a circulating system for the circulation of the plating solution from and to the plating tank, a plurality of settling tanks connected in parallel in the circulating system for receiving the plating solution from the plating tank, means associated with each of the settling tanks for isolating either of them, means associated with the settling tanks for refrigerating the plating solution contained therein to effect the crystallization and settling of impurities from the solution, a heat exchanger associated with the circulating system whereby heat from the plating solution flowing from the plating tank is transferred to the plating solution flowing to the plating tank, and means for flushing out the circulating system to remove impurities from the unisolated settling tank without interrupting the refrigeration of the solution in the isolated tank.

2. Apparatus for the continuous removal of impurities from plating solutions comprising, in combination, a plating tank for containing the plating solution, a circulating system for the circulation of the plating solution from and to the plating tank, a plurality of settling tanks connected in parallel in the circulating system for receiving the plating solution from the plating tank, means associated with each of the settling tanks for isolating either of them, means associated with the settling tanks for refrigerating the plating solution contained therein to effect the crystallization and settling of impurities from the solution, a heat exchanger associated with the circulating system whereby heat from the plating solution flowing from the plating tank is transferred to the plating solution flowing to the plating tank, and means forcing a fluid under pressure through the circulating system to remove impurities from the unisolated settling tank without interrupting the refrigeration of the solution in the isolated tank.

3. Apparatus for the continuous removal of impurities from plating solutions comprising, in combination, a plating tank for containing the plating solution, a circulating system for the circulation of the plating solution from and to the

plating tank, a plurality of settling tanks connected in parallel in the circulating system for receiving the plating solution from the plating tank, means associated with each of the settling tanks for isolating either of them, means associated with the settling tanks for refrigerating the plating solution contained therein to effect the crystallization and settling of impurities from the solution, a heat exchanger associated with the circulating system whereby heat from the plating solution flowing from the plating tank is transferred to the plating solution flowing to the plating tank, means for disconnecting the circulating system from the plating tank, and means for flushing out the circulating system when it is disconnected from the plating tank to remove impurities from the unisolated settling tank without interrupting the refrigeration of the solution in the isolated settling tank.

4. Apparatus for the continuous removal of impurities from plating solutions comprising, in combination, a plating tank for containing the plating solution, a circulating system for the circulation of the plating solution from and to the plating tank, means associated with the circulating system for forcing the circulation of the plating solution under pressure from and to the plating tank, a plurality of settling tanks connected in parallel in the circulating system for receiving the plating solution from the plating tank, means associated with each of the settling tanks for isolating either of them, means associated with the settling tanks for refrigerating the plating solution contained therein to effect the crystallization and settling of impurities from the solution, a heat exchanger associated with the circulating system whereby heat from the plating solution flowing from the plating tank is transferred to the plating solution flowing to the plating tank, and means for flushing out the circulating system to remove impurities from the unisolated settling tank without interrupting the refrigeration of the solution in the isolated tank.

5. Apparatus for the continuous removal of impurities from plating solutions comprising, in combination, a plating tank for containing the plating solution, a circulating system for the circulation of the plating solution from and to the plating tank, a plurality of settling tanks connected in parallel in the circulating system for receiving the plating solution from the plating tank, means associated with the circulating system for forcing the plating solution to the settling tanks under pressure, means associated with each of the settling tanks for isolating either of them, means associated with the settling tanks for refrigerating the plating solution contained therein to effect the crystallization and settling of impurities from the solution, means associated with the circulating system for forcing the purified plating solution under pressure from the settling tanks to the plating tank, a heat exchanger associated with the circulating system whereby heat from the plating solution flowing from the plating tank is transferred to the plating solution flowing to the plating tank, and means for flushing out the circulating system to remove impurities from the unisolated settling tank without interrupting the refrigeration of the solution in the isolated tank.

6. Apparatus for the continuous removal of impurities from plating solutions comprising, in combination, a plating tank for containing the plating solution, a circulating system for the circulation of the plating solution from and to the

- plating tank, means associated with the circulating system for forcing the circulation of the plating solution under pressure from and to the plating tank, a plurality of settling tanks connected in parallel in the circulating system for receiving the plating solution from the plating tank, means associated with each of the settling tanks for isolating either of them, means associated with the settling tanks for refrigerating the 5 plating solution contained therein to effect the crystallization and settling of impurities from the solution, a heat exchanger associated with the circulating system whereby heat from the plating solution flowing from the plating tank is transferred to the plating solution flowing to the plating tank, means for disconnecting the circulating system from the plating tank, and means for flushing out the circulating system when it is disconnected from the plating tank to remove 10 impurities from the unisolated settling tank without interrupting the refrigeration of the solution in the isolated settling tank.
7. Apparatus for the continuous removal of impurities from plating solutions comprising, in combination, a plating tank for containing the plating solution, a circulating system for the circulation of the plating solution from and to the plating tank, a heat exchanger associated with the circulating system for effecting the transfer 15 of heat from the plating solution withdrawn from the plating tank to the plating solution as it is returned to the plating tank, a plurality of settling tanks associated with the circulating system for receiving the plating solution from the plating tank, means associated with the settling tanks for refrigerating the plating solution to effect the crystallization and settling of impurities from the solution in the settling tanks, a plurality of valves associated with each of the settling tanks for isolating it to prevent the flow of 20 additional plating solution in the settling tank, 25 said plurality of valves disposed to be separately operable to permit withdrawal of the purified plating solution while preventing the admission of impure solution to one of the settling tanks while admitting impure solution to the other settling tanks, a plurality of valves associated with the settling tanks for refrigerating the plating solution to effect the crystallization and settling of impurities from the solution in the settling tanks, a plurality of valves associated with each of the settling tanks for isolating it to prevent the flow of 25 additional plating solution in the settling tank, 30 said plurality of valves disposed to be separately operable to permit withdrawal of the purified plating solution while preventing the admission of impure solution to one of the settling tanks while admitting impure solution to the other settling tanks but preventing its withdrawal, means for disconnecting the circulating system from the plating tank, and means for flushing out the disconnected circulating system while any one of the settling tanks containing the plating solution is isolated to remove the settled impurities from the unisolated settling tank without interrupting the refrigeration of the solution in the isolated settling tank.

venting its withdrawal, means for disconnecting the circulating system from the plating tank, and means for flushing out the disconnected circulating system while any one of the settling tanks containing the plating solution is isolated to remove the settled impurities from the unisolated settling tank without interrupting the refrigeration of the solution in the isolated tank.

5

8. Apparatus for the continuous removal of impurities from plating solutions comprising, in combination, a plating tank for containing the plating solution, a circulating system for the circulation of the plating solution from and to the plating tank, means associated with the circulating system for forcing the circulation of the 15 plating solution under pressure from and to the plating tank, a heat exchanger associated with the circulating system for effecting the transfer of heat from the plating solution withdrawn from the plating tank to the plating solution as it is 20 returned to the plating tank, a plurality of settling tanks associated with the circulating system for receiving the plating solution from the plating tank, means associated with the settling tanks for refrigerating the plating solution to effect the crystallization and settling of impurities from the solution in the settling tanks, a plurality of valves associated with each of the settling tanks for isolating it to prevent the flow of 25 additional plating solution in the settling tank, 30 said plurality of valves disposed to be separately operable to permit withdrawal of the purified plating solution while preventing the admission of impure solution to one of the settling tanks while admitting impure solution to the other settling tanks 35 but preventing its withdrawal, means for disconnecting the circulating system from the plating tank, and means for flushing out the disconnected circulating system while any one of the settling tanks containing the plating solution is isolated to remove the settled impurities from the unisolated settling tank without interrupting the refrigeration of the solution in the isolated tank.
